UNITED STATES PATENT OFFICE.

ROBERT BARRIE, OF PHILADELPHIA, PENNSYLVANIA.

VALVE MECHANISM FOR MOTORS, METERS, &c.

SPECIFICATION forming part of Letters Patent No. 630,643, dated August 8, 1899.

Application filed April 28, 1898. Serial No. 679,116. (No model.)

To all whom it may concern:

Be it known that I, ROBERT BARRIE, a citizen of the United States, residing in the city and county of Philadelphia, in the State of Pennsylvania, have invented a new and useful Valve Mechanism, of which the following is a specification.

My invention relates to that class of devices used to control steam, air, gas, or water under pressure in and out of separate chambers, as found in pumps, motors, and liquid-meters.

My invention consists of a central transversely-supported double-arm rocker, a convex-seated D slide-valve made to register with transverse elongated openings or ports, all of which are located centrally between connected twin piston-heads and inclosed within a single main cylinder, as will herein-after appear.

Figure 1 represents a vertical pressure-receiving rod S. Fig. 2 shows connecting-link K. Fig. 3 represents an isometrical view of double-arm rocker L. Fig. 4 represents isometrically the valve V. Fig. 5 shows a plan view of convex or under side of V. Fig. 6 is a side elevation of mechanism arranged with-in a cylinder shown in vertical longitudinal section.

In referring to accompanying drawings, C represents a main cylinder provided with longitudinal ports which form passage-ways from the center within said cylinder to the opposite ends thereof. Other openings I and O lead to or connect with the inlet and outlet pipes, respectively. C is also provided with a central vertical stuffing-box B and suitable end caps H and base, as required. The twin piston-heads P are provided with usual packing-rings and are connected together by rods R, or they may be formed from one casting within the chamber. Between the heads and over the port-holes is placed a convex-seated slide-valve V, a cavity n upon the under side thereof serving to alternately connect the passage-ways with the outlet O. This valve has also transverse vertical projections having flat surfaces Y, the guide-rod bearings T, and may or may not require the stops m.

Above this valve V on a central transverse

rod N is a double-arm rocker L, the lower arms X' of which straddle the rod R' and are brought in contact with the flat surface Y. By means of a link (see Fig. 2) the upper arm of the rocker connects with a vertical rod S, 55 that passes through a stuffing-box B. When required, the end of N may also project through a similar box for purposes herein-after explained. To the outward end of S may be attached means for depressing said rod. 60 For this purpose I find a weight W simplest in application, but prefer metal springs where quickness of motion is required. The end of this rod S may also connect with a train of recording-dials, as used in liquid- 65 meters, being inclosed by a cover D.

It will be evident that in the introduction of vapor or liquid under pressure through I said liquid would pass in direction of arrows and move the piston to the left, this action being 70 the same as that of a reciprocating steam-engine. Having reached a given point of a longitudinal movement, the adjustable pushers A strike L near x and through the link K impart an upward movement to S, overcoming 75 the depressing weight or springs until L has passed forward and beyond a vertical line or center through S, when L will receive a quick forward thrust by reason of aforesaid depressing weight or springs, and the lower arms X' 80 striking V upon Y will actuate the valve and change the connections of the passages or ports and outlet O and will cause the piston to move to the left, or vice versa, the displacement of the piston being regulated by 85 A, and thus measuring the quantity of liquid passing through. It will be evident that by suitable pawl-and-ratchet gear motion may be transmitted from S to usual registering mechanism; also, that a rod may be secured to P 90 and be made to pass through H and then converted by means of crank into rotary motion. In this case N should extend outward through a stuffing-box similar to B, when it may be connected to crank-shaft by usual means now 95 in use, and thus operate the inner valve V in unison therewith. I am aware that S may be raised by L through a cam movement, replacing link K, also that A may be secured to L instead of P, and thus accomplish the same 100

results. Therefore I do not desire to confine myself to the construction of these parts as shown, as

What I claim as new, and desire to secure 5 by Letters Patent, is—

1. A cylinder having a continuous straight bore of even diameter throughout its length, ports opening into said cylinder at each end thereof and also near the middle thereof, an 10 inlet and outlet port opening near the middle thereof, and a convex-seated **D** slide-valve within the cylinder and controlling the flow of fluids in said ports substantially as shown and for the purpose set forth.
- 15 2. A cylinder having a straight bore of even diameter throughout its length, said cylinder consisting of a single piece of metal and having ports opening into each end thereof and also near the middle thereof, an outlet-port 20 opening into the cylinder near the middle

thereof and a convex-seated slide-valve within the cylinder and controlling the flow of fluid in said ports, substantially as shown and for the purpose set forth.

3. The combination with a cylinder of connected twin piston-heads **P** **P'** slide-valve **V** between said piston-heads having contact-surfaces **Y** fluid-passages having ports controlled by said slide-valve, double-arm rocker **L** one end of which is adapted to strike said 25 contact-surfaces, rod **S**, link **K** connecting said rocker with said rod means for communicating continuous pressure to said rod, and projections **A** **A'** on said piston-heads all substantially as described and for the purpose 30 set forth.

ROBERT BARRIE.
